UNITED STATES PATENT OFFICE

2,439,150

INTERNAL-COMBUSTION ENGINE

Frederick H. Smith, Buffalo, N. Y.

Application March 31, 1943, Serial No. 481,224

2 Claims. (CL 123—43)

1

This invention relates to an internal combustion engine and more particularly to a four cycle internal combustion engine in which the pistons act against a single cam track, in converting the reciprocating motion of the pistons into rotary motion, in contradistinction to the usual crank shaft.

One of the principal objects of the invention is to provide such an internal combustion engine with explosions occurring during each revolution and which is inherently balanced without a crank shaft, and which has a constant maximum lever arm thereby to eliminate the dead center top and bottom pause which is incident to the use of a crank shaft.

Another object of the invention is to provide a reliable, lightweight, high power and high speed internal combustion engine of this type which can be used as an airplane engine.

Another object is to provide such an internal combustion engine which is very compact and also is self-contained.

Another object is to provide such an internal combustion engine which will stand up under conditions of severe and constant use and also in which sliding parts are avoided in the drive connection between the pistons and the oval cam track against which they act.

Another object is to provide such an internal combustion engine which is composed of simple castings and parts and readily lends itself to mass production methods.

Another object of the invention is to provide such an internal combustion engine which can be adapted to any type of fuel and in which the admission and control of the air and fuel can be effected in a simple and efficient manner.

Another object of the invention is to provide such an internal combustion engine which can be either of the rotating or stationary cylinder type.

Another object is to provide a simple and effective ignition system which insures combustion of the charges of the several cylinders in proper sequence.

Another object of the invention is to provide a simple and effective means whereby the form of the oval track can be varied to vary the inlet or suction time or stroke with reference to the exhaust time or stroke thereby to permit increased expansion of the gases and increasing the volumetric efficiency of the engine.

Another aim is to provide such an internal combustion engine in which the cylinders and their end heads are an integral unit.

2

Another object of the invention is to provide such an internal combustion engine which can be operated as a Diesel motor.

Another object is to provide such a motor having a large bore extending through the cylinder block among the several cylinders thereof and through which central cooling of the cylinder block can be effected.

Another object is to provide such a motor in which this relatively large bore extending through the cylinder block and among the several cylinders can be used to carry the intake and exhaust manifolds for the motor.

Another object is to provide such an internal combustion engine in which this relatively large cylindrical bore extending through the cylinder block and among the several cylinders is arranged coaxially of the axis of rotation of the cylinder block so that a cannon can be fired through this bore, thereby to adapt the invention to this particular type of fighter plane.

Another object of the invention is to provide such an internal combustion engine in which the various walls of the cylinder block are of thin cross section thereby to reduce the weight of the motor to a minimum and also increase the cooling efficiency thereof.

Other objects and advantages will appear from the following description and drawings in which:

30 Fig. 1 is a vertical section taken transversely of the axis of rotation through an internal combustion engine embodying my invention, this section being taken on line 1—1, Fig. 2.

35 Fig. 2 is a vertical section taken parallel with the axis of rotation, this section being taken on line 2—2, Fig. 1.

40 As shown in the accompanying drawings, the internal combustion engine embodying my invention includes a rotating cylinder block 5 which is shown as formed to provide six cylinders 6 or more, the axes of these cylinders being arranged tangential to a common circle coaxial with the axis of rotation of the cylinder block and the inner closed end of each of these cylinders being arranged adjacent the outer open end of the next preceding cylinder.

45 In each of the cylinders 6 is arranged a piston 7 which can be of any usual and well known construction and is shown as having the usual piston rings and to each piston is rigidly secured a connecting or piston rod 8. The outer end of each of the piston rods 8 traverses a stationary cam track, indicated generally at 10, this cam track being shown as oval in form, although its 50 shape can be varied to obtain a differential in the

length of the inlet and exhaust strokes of the pistons.

The stationary cam track 10 is shown as comprising a relatively wide oval or elliptical inner rail 11 secured to the inner face of a narrower oval elliptical supporting ring 12 thereby to provide a rail having outwardly facing shoulders 13 at its opposite sides.

The track 10 is carried by a stationary spider indicated generally at 14, this spider comprising spaced end rings 15, 16 which are preferably L-shaped in cross section, and integrally formed arched arms 17 which connect the two end rings 15, 16 and arch outwardly to carry the oval track 10, the supporting ring 12 of this track being secured to the centers of these arched arms. While the spider 14 can have any number of arched arms 17 to carry the oval rail 10, six are shown in the drawings.

In each of the end rings 15, 16 of the spider 14 is fitted the outer race of a main bearing 20, the inner races of these bearings being carried by a ring 21 which in turn is secured, in any suitable manner, to the corresponding end of the engine block 5. It will therefore be seen that the cylinder block 5 is free to rotate in the main roller bearings 20 carried by the stationary spider 14 and which spider also carries the oval track 10.

The fixed piston or connecting rods 8 work against the inner rail 11 of the oval track and for this purpose the outer end of each of the piston rods 8 is bifurcated to provide two arms 24 which embrace the inner rail 11 of this track. Between these arms of each piston is arranged a relatively large thrust roller 25, the axis of which is arranged parallel with the axis of rotation of the cylinder block 5 and the thrust of these rollers being against the inner elliptical face 26 of the rail 11. The outer end of each of the arms 24 of each piston rod is also shown as carrying a small outboard roller 28 which can engage the corresponding outwardly facing shoulder 13 of the rail 11, although these small rollers 28 are not essential to the operation of the engine.

With the above arrangement of elliptical cam track and tangentially arranged pistons, it will be seen that one revolution of the cylinder block 5 effects two reciprocations of each of the pistons 7. Thus, while each roller 25 is passing from point A to point B on the rail 11 of the oval track 10, its piston 7 is moved inwardly a complete stroke, as indicated by the arrow associated with the left hand piston in Fig. 1. This movement of each piston while its roller is traveling from point A to point B can therefore be utilized as the compression stroke of the engine.

While the rollers 25 are moving from point B to point C of the elliptical track the corresponding piston 7 moves outwardly, this movement being indicated by the arrow associated with the lowermost cylinder in Fig. 1. Therefore, this movement can be used to provide the firing stroke of the engine.

When each roller 25 moves from the point C to the point D, the corresponding piston 7 is moved inwardly as indicated by the arrow associated with the right hand cylinder in Fig. 1. Therefore, this movement can be utilized to provide the exhaust stroke of the engine.

When each roller 25 moves from the point D to the point A on the elliptical track, the corresponding piston is moved outwardly as indicated by the arrow associated with the uppermost cylinder in Fig. 1. Therefore, this move-

ment of each piston can be utilized to provide the intake stroke of the engine. It will accordingly be seen that as the cylinder block rotates the oval or elliptical cam track 10 provides a four cycle action, each piston being carried through a compression, firing, exhaust and intake stroke in this revolution of the cylinder block.

To provide the charge of fuel and air for the intake stroke of each piston, the integral end ring 16 of the supporting spider 14 is shown as formed to provide a bracket 30 on which a carburetor (not shown) can be mounted. The air from the carburetor mounted on the bracket 30 is drawn through a duct 31 into an annular stationary intake manifold 32, this annular stationary intake manifold being U-shaped in cross section and being open on its inside and provided with straight side walls. The entire cylinder block 5 is formed to provide a large bore 34 extending therethrough and coaxial with its axis of rotation and at its center the cylinder block 5 is formed to provide an integral inwardly extending annular flange 35. A sleeve 36 is fitted in this bore 34 at the end thereof adjacent the annular stationary intake manifold 32 and this sleeve is formed to provide a radially outwardly extending flange 38 which is in closely spaced relation to the inner vertical side wall of the annular stationary intake manifold 32. To prevent air from being drawn through the space between the rotating flange 38 and the adjacent inner side wall of the annular stationary intake manifold 32, a labyrinth seal 39 is preferably provided.

The sleeve 36 and its flange 38 forms one wall of an annular rotating intake manifold passage 40 of the engine and the other wall of this annular rotating intake manifold is formed by a sheet metal drum 41 having an inwardly extending annular flange 42 at its inner end which can be secured to the inwardly extending flange 35 of the motor block 5 by bolts 43; and having a cylindrical part which is in contact with the bore 34 of the cylinder block 5; and also having a reduced portion 45 which is spaced from the sleeve 36 to provide the annular intake manifold space 40. At its outer end the sheet metal drum 42 is formed to provide a radially outwardly extending flange 46 which is disposed in closely spaced relation to the outer straight wall of the annular stationary intake manifold 32. To prevent leakage between the rotating flange 46 and the annular stationary intake manifold 32, a labyrinth seal 48 is provided therebetween.

The air and fuel from the annular intake manifold 40 is drawn into each of the cylinders 6 through an intake passage 50 formed in the cylinder block and under control of an intake valve indicated generally at 51. While any suitable valve can be employed each of the valves 51 is shown as being a poppet valve comprising a cylindrical valve body 52 having an inlet opening 53 registering with the corresponding opening 50 in the cylinder block and having a seat at its inner end against which the head 54 of the valve seats. This head is shown as having a stem which is slidably carried by a small sleeve 55 arranged in the center of the valve body and the valve is shown as yieldingly held in its closed position by a helical compression spring 56. The outer end of the stem of the valve is shown as held against a sliding tappet pin 60 which is mounted in a horizontal guideway 75 formed in the corresponding end ring 21 of the

cylinder block 5 and carries a roller 62. This roller engages a cam track 63 provided on the inner face of the ring 16 of the supporting spider 14 and this cam track 63 is formed to provide a salient face so as to open each intake valve 51 as the corresponding piston traverses its intake cycle. This would be those pistons whose rollers 25 are traversing the elliptical track from the point C to the point D with the operation first assumed. At other times the valves 51 remain closed under the influence of their springs 56.

The passage 65 through which fuel and air is drawn into each cylinder 6 under control of its intake valve 51 also serves as the exhaust passage for each cylinder. The exhaust of each cylinder is under control of an exhaust valve 51a which is shown as being identical in construction to the corresponding intake valve 51 and the description is hence not repeated, the same numerals being applied to the exhaust valve 51a and distinguished from the corresponding parts of the intake valve by the suffix a. The cam track for the exhaust valves, designated at 63a, is likewise similar to the cam track controlling the intake valves 51 except that its salient part is arranged to open the exhaust valves 51a as the pistons traverse the exhaust cycle. Under the condition of operation first assumed this would be when the rollers 25 on the piston rods 8 are traversing the elliptical track from the point C to the point D.

The left hand end of the crank case 5, as viewed in Fig. 2, is formed to provide a cylindrical extension 10 which has a radially extending flange 11, this flange being provided with bolt holes 72 which permit of attaching the propeller (not shown) directly to the cylinder block or to a gear drive mechanism.

Each of the exhaust valves discharges into a passage 50a provided in the cylinder block and thence into an annular exhaust manifold 74 formed within the bore 34 of the cylinder block by a sheet metal drum 75. This sheet metal drum is shown as having an inwardly extending annular flange 76 at its inner end which is secured by the bolts 43 to the central inwardly projecting flange 35 of the cylinder block 5 and as having an adjacent cylindrical part 77 which fits into the bore 34. Beyond this the drum 75 is contracted, as indicated at 78, so as to form the exhaust manifold space 74 and at its outer extremity the drum is formed to provide an axially extending flange 79 which can be secured, in any suitable manner, within the cylindrical extension 70 of the cylinder block.

To relieve the exhaust from the annular exhaust manifold 74 the left hand extension of the cylinder block 5 is formed to provide a plurality of ports 80 leading from the exhaust manifold space 74 to the exterior of the cylindrical extension 70 of the cylinder block. These ports 80 lead into the space between a pair of sheet metal flanges 81 which are secured to the exterior of the cylindrical extension 70 in any suitable manner and are embraced by a stationary annular exhaust manifold 82. As with the annular stationary intake manifold 32, the annular stationary exhaust manifold 82 is U-shaped in cross section and is provided with straight side walls which are arranged in closely spaced relation to the flanges 81, leakage being prevented therebetween by labyrinth seals 83.

The stationary exhaust manifold 82 is provided with an exhaust duct 84 at one side.

The firing of the cylinders can be effected by 75

means of a track and a contactor traversing this track. For this purpose the ring 16 of the spider 14 is shown as carrying a track 85 of insulating material which can be provided along a part of its length with a strip of metal 86 connected to a source of high tension current. Each of the cylinders is shown as having a contactor 87 which can be pivotally secured to the cylinder block 5 in any suitable manner and arranged to traverse the track 85 and its strip of metal. Each contactor is shown as connected by a wire 88 with a spark plug 89 for the corresponding cylinder.

The metallic strip 86 is provided in the track 85 of insulating material in proper position to effect firing of the cylinders in proper sequence. This, under the operation assumed, would be at the end of the compression stroke and at the beginning of the firing stroke, this being when each roller 25 traverses the point B of the elliptical track.

In the operation of the engine as above described, the cylinder block 5 rotates counterclockwise, as viewed in Fig. 1, and when each roller 25 passes beyond the point C of the oval track 10, the corresponding piston 7 is moved inwardly. At this point the salient part of the cam track 63a moves the pin 60a to the right, as viewed in Fig. 2, thereby to open the exhaust valve 51a against the resistance of the return spring 56a. The inward movement of this piston thereby causes the spent products of combustion to be exhausted through its passage 65, open valve 51a, passages 63a and 50a, rotating exhaust manifold 74 and through the passages 80 in the cylindrical extension 70 of the cylinder block into the annular stationary exhaust manifold 82 and through its outlet 84 to the atmosphere. The escape of exhaust gases from between the stationary annular exhaust manifold 82 and the flanges 81 on the cylindrical extension 70 of the cylinder block is prevented by the labyrinth seals 83.

When each roller 25 reaches the point D of the elliptical track, the roller 62a of the exhaust valve 51a associated with its cylinder passes beyond the salient part of the cam track 63a so that its exhaust valve 51a closes under the influence of the return spring 56a. At the same time the form of the oval track 10 causes the corresponding piston 7 to move outwardly. At this time the roller 62 of the corresponding intake valve 51 encounters the salient part of the track 63 so that the pin 60 and valve 51 are moved to the left, as viewed in Fig. 2, against the resistance of the return spring 56. The outward movement of the piston 7 thereby draws a charge of combustible mixture into the cylinder, this being supplied by the carburetor (not shown) mounted on the bracket 30 and being drawn through the duct 31 and stationary annular intake manifold 32 into the rotating annular manifold 40. As with the exhaust manifold, labyrinth seals 39 and 48 are provided between the stationary and rotating parts of the intake manifold to prevent air from being drawn into the manifold 40 except through the carburetor. The charge is drawn into the cylinder through the passages 50 and 53, past the open intake valve 51 and through the passage 65 into the cylinder.

When the roller 25 of each piston reaches the point A of the oval track 10, the roller 62 and its associated intake valve passes beyond the salient part of the cam track 63 so that the corresponding intake valve 51 closes under the in-

fluence of its return spring 58. As each roller 25 continues beyond the point A of the elliptical track, the corresponding piston 7 is forced inwardly so as to compress the combustible mixture in the cylinder.

The piston 7 reaches the end of its compression stroke when its roller 25 passes the point B in the oval track 10, and at this time the corresponding contactor 87 rides into engagement with the metallic strip 86 on the track 85 of insulating material so that high tension current is supplied from this strip through the contactor 87 and wire 88 to the corresponding spark plug 89. The compressed charge within the cylinder is thereby ignited.

The expansion of the gas in the cylinder thereby drives the piston outwardly, this comprising the power stroke of the engine and during which stroke the corresponding thrust roller 25 is traversing the elliptical track from point B to point C.

With the engine as above described, it will be seen that it is not essential that the cam track 10 be truly elliptical and that the shape of this cam track can be varied to adjust the time of the strokes of the piston during any desired cycle. For example, by elongating the elliptical track, as shown by dotted lines in Fig. 1, a longer intake and compression stroke in point of time is provided in relation to the power stroke, thereby to draw a greater volume of air into each cylinder and increase the volumetric efficiency of the engine. Further, it will be understood that supercharged air could be supplied through the carburetor to the engine.

It will be noted that by providing the large axial bore 34 through the cylinder block, the cylinder block can be centrally cooled thereby to simplify the problem of maintaining the desired operating temperature of the motor. Further, it will be seen that the design of the motor provides thin cylinder block sections throughout so as to provide high cooling efficiency. It will also be seen that the large axial bore, through the cylinder block, permits of discharging a cannon axially through the motor so as to render the motor particularly applicable to combat planes. The motor can also be of the internal combustion type as shown, or can be readily modified to operate on the Diesel principle.

I claim as my invention:

1. An internal combustion engine, comprising a cylinder block having a large bore extending therethrough and having a plurality of cylinders with their axes tangential to a circle concentric with said bore, an oval cam track surrounding said cylinder block and arranged in the plane of the axes of said cylinders, said cylinder block and oval cam track being rotatable relative to each other about the axis of said bore, a piston in each of said cylinders, a piston rod secured to and maintained in substantially coaxial relation to each piston and having thrust engagement with said track, a ring-shaped stationary intake manifold adjacent to and concentric with one end of said bore and having an inlet opening and an outlet-opening through which a combustible mixture is supplied to said cylinders, a ring-shaped rotatable intake manifold secured within said bore and directly coacting with said annular stationary intake manifold to receive the combustible mixture therefrom, a passage leading from

said annular rotatable intake manifold to each of said cylinders, an inlet valve arranged at the side of the corresponding cylinder and controlling the flow of the combustible mixture through each of said passages, means for exhausting each of said cylinders, means for igniting the combustible charge in each of said cylinders, and means for actuating said valves, exhausting means and igniting means in a sequence to effect said relative rotation of said cylinder block and oval cam track through the thrust of said piston rods against said oval cam track, said rotatable intake manifold defining a large, unobstructed tubular coaxial passage extending completely through the engine.

2. An internal combustion engine, comprising a cylinder block having a large bore extending therethrough and having a plurality of cylinders with their axes tangential to a circle concentric with said bore, an oval cam track surrounding said cylinder block and arranged in the plane of the axes of said cylinders, said cylinder block and oval cam track being rotatable relative to each other about the axis of said bore, a piston in each of said cylinders, a piston rod secured to and maintained in substantially coaxial relation to each piston and having thrust engagement with said track, a ring-shaped stationary exhaust manifold adjacent to and concentric with one end of said bore and having an outlet opening and an inlet opening, a ring-shaped rotatable exhaust manifold secured within said bore and directly coacting with said ring-shaped stationary exhaust manifold to discharge the products of combustion therefrom, an exhaust passage leading from each cylinder to said annular rotatable exhaust manifold, an exhaust valve arranged at the side of the corresponding cylinder and controlling the flow of the products of combustion through each of said exhaust passages, means for admitting a combustible charge to each of said cylinders, means for igniting the charge in each of said cylinders, and means for actuating said admitting means, igniting means and exhaust valves in a sequence to effect relative rotation of said cylinder block and oval cam track through the thrust of said piston rods against said oval cam track, said rotatable exhaust manifold defining a large, unobstructed passage extending completely through the engine.
